UNITED STATES PATENT OFFICE

ERNEST W. DAVIS, OF OAK PARK, ILLINOIS, ASSIGNOR TO ALEMITE CORPORATION, OF CHICAGO, ILLINOIS, A CORPORATION OF DELAWARE

LUBRICATING APPARATUS

Application filed October 21, 1929. Serial No. 401,054.

My invention relates generally to lubricant compressors, commonly called "grease guns", which are used to force lubricant under high pressure into fittings attached to bearings to be lubricated. More particularly my invention relates to improvements in high pressure guns of the type in which the connection with the fitting and the compression of the lubricant are accomplished by a single longitudinal movement of the compressor handle toward the lubricant receiving fitting.

It is an object of my invention to provide an improved grease gun of the above mentioned type which has a high pressure cylinder and piston and a simple and effective means for priming the high pressure cylinder.

It is an object of my invention to provide an improved grease gun containing a spiral 20 or helical conveyor to advance lubricant to the high pressure discharge cylinder for priming same for the next stroke.

A further object of my invention is to provide novel and improved means for rotating 25 the barrel of the grease gun during a discharge stroke, thereby to compress lubricant for charging the high pressure cylinder.

A further object is to provide a grease gun which is easily operated, positive in its action 30 and which may be easily manufactured and assembled.

Other objects and advantages will appear 35 from the following description, reference being had to the accompanying drawing, in which:

Fig. 1 is a central longitudinal section of the grease gun;

Fig. 2 is a fragmentary side view of a portion of the gun; and

Fig. 3 is a transverse sectional view taken on line 3—3 of Fig. 1.

In the embodiment of my invention illustrated in the drawing I have shown a grease gun having a barrel 4 substantially cylindrical in shape, closed at its upper end by a cap 6 and converging at its lower end to a smaller cylindrically shaped portion 8 that is internally threaded as shown at 14 to receive a high pressure cylinder 12. A nozzle 16 is secured to the lower end of cylinder 12 and car-

ries a spring pressed check valve 18 normally closing the end of the bore of the cylinder. The upper end of cylinder 12 extends into the reduced portion 8 of the grease gun barrel 4.

A plurality of inlet ports 20 are provided near the upper end of cylinder 12. A plunger 22 for discharging lubricant under high pressure enters the end of cylinder 12 and is normally held in the position shown in the drawing (Fig. 1) by a compression spring 24 positioned between a shoulder 26 formed by boss 10 and a fixed washer 28 resting against a shoulder 29 of plunger rod 30.

Plunger rod 30 is square in cross-section (see Fig. 3) for a purpose which will later be apparent, and extends up through cap 6, carrying a pawl supporting collar 32 and provided at its upper end with an operating handle 34.

Rod 30 is guided in a sleeve 36 also square in cross-section, which bears at its lower end against washer 28 and is provided at its upper end with a flange 38, a reduced portion 39 and a threaded portion 40. Reduced portion 39 passes through an aperture 42 in cap 6 and forms an annular bearing therefor, the sleeve being held against longitudinal movement between flange 38 and a cap nut 44 screw-threaded over the end of sleeve 36. A spiral conveyor blade 46 is rigidly fastened 50 to sleeve 36 and so constructed that its peripheral edge is in close proximity to the inner face of the barrel wall.

Pawl and ratchet means for revolving barrel 4 are provided and may comprise the 55 ratchet teeth 48 formed upon the upper surface of cap 6, and a pair of pawls 50 carried by supporting collar 32 pinned to the rod 30. Pawls 50 are mounted upon shouldered screws 52 and are provided with torsion 60 springs 54 for returning the pawls to normal position after each stroke.

To fill the compressor cap 6 is unscrewed and rod 30 with all the elements attached thereto is withdrawn from the barrel. Grease 65 is placed in barrel 4 and conveyor blade 46 is rotated as it is forced into the barrel, in effect being screw-threaded into the grease. After cap 6 is securely threaded into place the gun is ready for operation. The operator, 70

grasping the handle 34, pushes the nozzle 16 against a lubricant receiving fitting attached to a bearing to be lubricated. A downward push on rod 30 causes plunger 32 to discharge grease from cylinder 12 through nozzle 16 under high pressure. As rod 30 descends pawls 50 engage the ratchet teeth 48 and revolve barrel 4.

The relative rotation of the barrel 4 and the conveyor blade 46 causes the grease to be forced downwardly and packs it into the cylindrical end portion 8 of the barrel. When the operator relieves the pressure of the nozzle against the fitting the spring 26 will force the plunger 22 upwardly, causing a partial vacuum within the cylinder 12. As soon as the plunger clears the ports 20 the grease in the cylindrical portion 8 of the barrel will flow into the cylinder, not only due to the fact that there is a partial vacuum in the cylinder but also due to the fact that the grease in the lower portion of the barrel and in the cylindrical portion 8 thereof is under slight compression. There is usually a small amount of air entrapped with the grease and this air is slightly compressed as the conveyor blade 46 forces the grease toward the lower end of the barrel. The conveyor and its operating mechanism thus serves as an adequate means to feed the lubricant from the barrel to the cylinder and to assure rapid and complete priming of the latter.

It will be obvious that the compressor may be filled in other ways than that mentioned, such, for example, as by providing a lubricant receiving fitting in a wall of barrel 4 to receive lubricant under pressure from a suitable source.

It will also be apparent that other means may be provided for revolving the barrel and I do not wish to limit myself to the specific construction shown. This invention is capable of wide variation within equivalent limits and I contemplate such variation as may be desirable or useful in the particular adaptation of the invention shown, or in its adaptation to other devices. I do not restrict myself in any unessential particulars, but what I claim and desire to secure by Letters Patent is:

1. A grease gun including a cylindrical container having a reduced portion at one end, a high pressure discharge cylinder mounted in said end, said high pressure cylinder being provided with a discharge nozzle, a plunger reciprocable in said cylinder, a plunger rod extending therefrom through the opposite end of said container, a handle on said rod, a guide sleeve surrounding said rod in said cylinder container, a spiral conveyor blade rigidly secured to said sleeve and extending to the lower end of said barrel, and pawl and ratchet means associated with said rod and said container for rotating said

container relative to said conveyor thereby to feed lubricant to said cylinder.

2. A grease gun including a cylindrical container having a reduced portion at one end, a high pressure discharge cylinder mounted in said end, said high pressure cylinder being provided with a discharge nozzle, a plunger reciprocable in said cylinder, a plunger rod extending therefrom through the opposite end of said container, a handle on said rod, a guide sleeve surrounding said rod in said cylinder container, a spiral conveyor blade rigidly attached to said sleeve and extending to the lower end of said barrel, and cooperating means between said rod and said container for rotating said container relative to said conveyor thereby to feed lubricant to said discharge cylinder under pressure.

3. A high pressure lubricant compressor comprising a barrel, a high pressure cylinder at one end of said barrel and in axial alignment therewith, a plunger in said cylinder, a helical lubricant conveyor rotatably mounted in said barrel for priming said high pressure cylinder, and common means for manually operating said plunger and said last-named means.

4. A high pressure lubricant compressor comprising a barrel, a high pressure cylinder at one end of said barrel in axial alignment and in communication therewith, a plunger in said cylinder, a helical conveyor for feeding lubricant from said barrel to said cylinder, and means for reciprocating said plunger and relatively rotating said barrel and conveyor.

5. A high pressure lubricant compressor comprising a barrel, a high pressure cylinder at one end of said barrel in axial alignment and in communication therewith, a plunger in said cylinder, a plunger rod integral therewith and extending through the opposite end of said barrel, a sleeve surrounding said rod in said barrel, a helical blade attached to said sleeve, and means for relatively rotating said barrel and said conveyor blade.

6. A high pressure lubricant compressor comprising a barrel, a high pressure cylinder at one end of said barrel in axial alignment and in communication therewith, a plunger in said cylinder, a plunger rod integral therewith and extending through the opposite end of said barrel, a sleeve surrounding said rod in said barrel, a helical blade attached to said sleeve, and means for rotating said barrel around said conveyor blade, said means including a ratchet on said compressor and a pawl carried by said plunger rod.

7. A high pressure lubricant compressor comprising a barrel, a high pressure cylinder at one end of said barrel, a nozzle carried at the discharge end of said cylinder and

adapted to make sealed contact with a lubricant receiving fitting, a plunger reciprocable in said cylinder, a helical conveyor in said barrel and rotatable relative thereto, and common means for reciprocating said plunger, causing relative rotation of said barrel and said conveyor, and forcing said nozzle against a lubricant receiving fitting.

8. In a grease gun, the combination of a high pressure lubricant pumping mechanism, with a lubricant reservoir, and a spiral conveyor blade extending the length of said reservoir, responsive to actuation of said pumping mechanism for feeding the grease in the reservoir to said pumping mechanism.

9. In a grease gun, the combination with a compression cylinder, a piston reciprocable therein, a reservoir, and a helical impeller blade movable about the axis of the reservoir, to form the sole means for feeding the grease therein to said compression cylinder.

10. In a portable hand operated grease gun, the combination of a compression chamber with a compressor element therefor, means for operating said compressor element, a tubular grease reservoir in communication with said chamber, a helical impeller blade movable responsive to actuation of said compressor element operating means in an annular path about the axis of said reservoir and forming the sole means for feeding the grease contained therein to said compression chamber.

11. In a portable hand operated grease gun, the combination of a compression chamber with a compressor element therefor, means for operating said compressor element, a tubular lubricant reservoir in communication with said chamber, a rotatable conveyor comprising a helical blade having an advanced face inclined to any plane passing through the axis of the reservoir to compact an engaged body of lubricant contained therein, said blade being movable relative to said reservoir responsive to actuation of said compressor element operating means for supplying grease to said compression chamber.

12. A high pressure grease gun comprising a barrel having an axial shaft, a helical blade mounted thereon, a high pressure cylinder associated with said barrel and supplied with lubricant therefrom, a plunger carried on said shaft for cooperation with said cylinder, a handle on said shaft for reciprocating said plunger, and means carried on said shaft for rotating said barrel relative to said helical blade simultaneous with the reciprocation of said plunger.

13. In a grease gun, the combination of a lubricant reservoir comprising a barrel having a shaft therein, lubricant ejecting mechanism associated with said barrel and supplied with lubricant therefrom comprising a high pressure cylinder having a plunger carried by said shaft reciprocable in said cylinder,

a helical blade mounted on said shaft for advancing lubricant to the cylinder of the ejecting mechanism, a handle on said shaft for reciprocating said plunger, and means for rotating said barrel relative to said blade simultaneous with the reciprocation of said plunger.

14. In a portable hand operated grease gun, the combination of a compression cylinder having a piston reciprocable therein with a reservoir for supplying lubricant to said cylinder, a helical conveyor blade in said reservoir directly engaging the body of grease therein and forming the sole means for feeding grease to said cylinder, and common manipulative means for effecting the operation of said conveyor blade to feed grease to said cylinder simultaneous with the actuation of said piston.

15. A high pressure lubricant compressor comprising a barrel, a high pressure cylinder at one end of said barrel and in communication therewith, a plunger in said cylinder, a helical conveyor extending the length of said barrel for feeding lubricant therefrom to said cylinder, and means for reciprocating said plunger and relatively moving said conveyor and barrel.

In witness whereof, I hereunto subscribe my name this 16th day of October, 1929.
